UNITED STATES PATENT OFFICE

2,049,006

AIRPLANE HAVING VARIABLE LIFTING SURFACES

Jacques Gerin, Boulogne-sur-Seine, France

Application April 4, 1935, Serial No. 14,681
In France April 7, 1934

6 Claims. (Cl. 244—12)

Airplanes having a variable lifting surface are already known, particularly by the United States Patents No. 1,787,517, dated 6th January 1931 and No. 1,979,194, dated 30th October 1934, in the name of the applicant, in which some of the fixed planes and, more especially, the lifting wings, devised for flight at a high speed, are transformed, for flight at low speed and for flying off or landing, into planes of the same span but of much greater depth, owing to flexible movable surfaces wound on drums or extended along fixed planes. The free end of each flexible surface is urged, in the direction for extension or unwinding, by a cable, or its equivalent, which passes to the end of the corresponding fixed lifting surface in order to wind up on a driving drum.

The present invention relates to improvements in airplanes of the type previously defined and is mainly characterized by the following points, applied separately or according to any combinations:

(a) A drum for winding up a cable for pulling out the flexible surface and a drum for winding up or retracting this flexible surface, are driven, from one and the same motor, rotating in both directions, through the medium of movement selecting devices, such as free wheels, with suitable speed reducing ratio, so that for pulling out the flexible surface, the free wheel driving the drum of this flexible surface should be actuated in its free direction with a certain lead, the free wheel driving the drum of the cable being actuated in the driving direction; for retracting the flexible surface, the free wheels are driven in directions reverse to those indicated.

(b) The motor is always directly connected to the free wheel of the drum for winding up the cable, the speed of rotation of this free wheel having a constant ratio relatively to that of the motor.

(c) The free wheel driving the drum for winding up the flexible surface is driven, in the winding up direction, by a first speed reducing device and at a lower speed than for the unwinding operation which is effected through the medium of a second speed reducing device, an automatic rocker ensuring the setting in action of the first or second speed reducing device, according to the direction of displacement of the flexible surface.

(d) Friction devices are combined with the drums.

(e) The rocker is mounted on the shaft of the motor or on a shaft directly driven by the latter,

through the medium of a friction device ensuring its temporary angular connection with said shaft, which rocker, in position of rest, does not allow any connection with the motor and the two speed reducing devices controlling the drum of the flexible surface.

(f) The closing of the circuit of the motor, for ensuring its displacement in one direction or the other, causes an angular displacement of the rocker in the same direction in order that it should come in engagement with a corresponding wedge-shaped contact ensuring, on the one hand, disengagement between the rocker and the motor and, on the other hand, the closing of the main circuit, this allowing to release the hand operated contact knob, as well as the closing of one of the electromagnets holding said rocker in the position of engagement of one of the speed reducing devices of the drum of the flexible surface with the motor.

(g) The end of the displacement of the flexible surfaces ensures the opening of the circuit of the motor and the opening of the circuit of the electromagnet holding the rocker which then returns to its intermediate position under the action of a resilient returning device.

(h) An end box or casing for each movable flexible surface is of rigid construction and it is perfectly guided on the corresponding fixed wing for constituting, on the one hand, a resistant element on which the flexible surface engages and, on the other hand, a stream-lined connection between the fixed wing and the fuselage, during retraction of the flexible surface.

(i) For limiting oblique stresses on the flexible surface, particularly during unwinding of the latter, use is made of a light carriage rolling on the front portion of the fixed wing so as to absorb these oblique stresses, said carriage being preferably combined with the rigid end box or casing.

(j) The movable flexible surface which, when wound up, is retracted within the fuselage for instance, determines at the beginning of its unwinding movement and in antagonism to the action of returning means, the opening of a shutter normally closing an opening provided for the passage of the flexible surface, this shutter constituting a guide for the latter.

(k) The returning means, constituted for instance by an elastic cable for each flexible surface, act, at the end of the movement of the latter and particularly on the corresponding rigid end box or casing, for completing the retraction of the flexible surface in case one of the movable flexible surfaces is completely wound up before

the other corresponding movable flexible surface, the circuit of the driving motor having been opened by the first retracting operation.

(l) Each movable shutter, normally held in closed position by the returning means, is connected to a cable which, in retracted position, is rigid with one of the elements of the corresponding flexible surface and particularly with its movable end box or casing; this cable moves in this box or casing at the beginning of the unwinding operation for opening the shutter in antagonism to the action of the returning sandow and it engages, after a movement of small amplitude, with a fixed part by disengaging from the movable flexible surface.

(m) The engagement of the cable with the movable flexible surface or with the fixed point is automatically ensured by the displacement of this flexible surface which acts, for that purpose, on a rocker engaging with the said cable for releasing the flexible surface or reversely.

(n) The control of the various drums from the motor is ensured by nonreversible devices, particularly of the worm and worm wheel type, for constituting a safety device.

(o) The motor for one and the same group of flexible surfaces can rotate in both directions, its current supply being controlled by the energization of either of two electromagnets which operate contacts for the flow of current in one direction or the other.

(p) A so-called "retracting" knob and another so-called "spreading out" knob ensure the energization of either of the electromagnets operating the contacts energizing the motor, the beam driven by the motor ensuring the closing of the contact which, in its turn, ensures the permanent closing of the circuit energizing the electromagnet put in action, when the knob previously actuated is released, the circuit being broken when the flexible surfaces act on so-called "extreme retracting" or "extreme spreading out" contacts, according to circumstances.

(q) When the flexible surfaces are being wound up or unwound, the action on the spreading out knob or on the retracting knob first causes the pre-established circuit to be broken and to stop the motor, then to close a supply circuit for imparting to the flexible surface a displacement reverse to that to which they were subjected.

The invention further relates to other features which will appear from the following description with reference to the accompanying drawings, given by way of example only, and in which:

Fig. 1 is a diagrammatic perspective view of a form of construction of the device for controlling the movable flexible surface.

Fig. 2 is a side view of a practical embodiment of the device diagrammatically illustrated in the preceding figure.

Fig. 3 is a corresponding elevation.

Fig. 4 is a partial plan view of the movable flexible surface in extended position on the fixed wing.

Fig. 5 is a partial view, on an enlarged scale of the end of the flexible surface or movable box or casing.

Fig. 6 is a corresponding side view.

Fig. 7 is a diagrammatic elevation of the device controlling the shutter closing the opening through which the flexible surface issues, this shutter being shown in open position.

Fig. 8 is a side view corresponding to the preceding figure.

Fig. 9 is a diagrammatic view of a control device of the electric motor actuating a group of flexible surfaces.

Fig. 10 is a front view of a board associated with this control device.

The control for the movable flexible surface is diagrammatically illustrated in Fig. 1 in order that it should be more clearly understood, this figure showing only an explanatory diagram of a form of construction, a practical embodiment of 10 which is illustrated in Figs. 2 and 3.

This control device comprises a main motor 1, which can rotate in both directions according to the manipulation of the control members which will be subsequently described with the electric 15 diagram of connections of the installations on board an airplane. This motor actuates a drum 2 on which winds a cable 3 passing for instance on a pulley 4 arranged at the end of one of the fixed lifting surfaces of the airplane. This cable 3 is 20 attached, at 5, to the end of the movable lifting surface 6 (diagrammatically illustrated) which is wound up, in retracted position, on a drum 7.

The drum 2 is driven by the motor 1 through the medium of a worm 8 fast on the shaft 9 of the 25 motor and meshing with a worm wheel 10 rigidly secured on a shaft 11 carrying another worm 12 meshing with a worm wheel 14. The latter drives the shaft 15, rigid with the drum 2, under the control of a movement selecting device 16 constituted by a free wheel.

On the other end of the shaft 9 of the motor 1 is rigidly secured a toothed wheel 17, which can mesh, through the medium of a rocker illustrated only in Figs. 2 and 3, either with a toothed wheel 25 18, or with a toothed wheel 19. The toothed wheel 18 is directly and rigidly secured on a shaft 20 carrying a worm 21 meshing with a worm wheel 22. The latter drives the shaft 23, carrying the drum 7, only in one direction owing to a movement selecting device 24 constituted by a free wheel. The gear 19 drives the shaft 20 through the medium of the shaft 25 and of gears 26, 27 and 28.

The worm and worm wheel mechanism constitutes a safety device.

The free wheel 16 loosely rotates in the direction of the arrow 30 and drives the shaft 15 only in the direction of the arrow 29. Likewise, the free wheel 24 loosely rotates in the direction of the arrow 31 and drives the shaft 23 in the direction of the arrow 32. Moreover, friction devices are combined with the drums, as will be described with reference to Figs. 2 and 3.

The directions of rotation of the various members, for unwinding the flexible surface, are indicated by uncrossed arrows, and the directions of rotation of these members, for winding up or retracting the flexible surface, are indicated by crossed arrows.

For unwinding the flexible surface, the motor 1 rotates in the direction of the arrow 34 and the drum 2 in the direction of the arrow 29. In this case, the toothed wheel 17 meshes with the toothed wheel 18 and the free wheel 24 is driven, 35 in the direction of the arrow 31, without acting on the shaft 23 of the drum 7, but with a certain lead relatively to this drum, in order that the unwinding pull, exerted by the cable 3 on the movable surface 6 which unwinds from the drum 7, should not be checked.

It will be indicated, by way of example only, that the applicant has chosen as gearing down ratio, between the shaft 9 of the motor 1 and the toothed wheel 14, the ratio 233,5. The gear 35

ing down between the shaft 9 and the toothed wheel 22, when the gear 18 is used, is chosen with a ratio of 256. The gearing down between the shaft 9 and the toothed wheel 22, when the gear 19 is used, is chosen with a ratio of 768. This variation of gearing down ratio is necessary in order that the winding up of the flexible surface on the drum 7 should be correctly effected, the latter being then driven by the motor which, in this case, rotates in the direction of the arrow 40, by utilizing the gear 19. In fact, it is necessary that the speed of the drum 2, when the cable 3 unwinds and is driven by the sail winding up on the drum 7, should remain lower than the speed of the wheel 14. This important difference in the ratios is due to the fact that the maximum diameter when the flexible surface is wound up is much larger than the winding up diameter of the drum 2 which remains constant. A brake, acting on the drum of the cable, allows of slightly stretching this cable between the drum and the flexible surface.

In the practical embodiment illustrated in Figs. 2 and 3, the motor is indicated at 1, the drum 2 for winding up the cable at 2, and the shaft of two drums on which two movable flexible surfaces wind up, are indicated at 23. The other parts are also indicated by the same reference numbers as in Fig. 1, but the gear 17 no longer acts directly on the gear 18 or on the gear 19, the transmission being ensured in this case through the medium of the gear 17^a, the latter meshing, either with the gear 19, or with the gear 18. The transmission between the gears 18 or 19 and the shaft 23 is ensured through the medium of various gears. Brakes 50, 51 and 52 are provided for exerting a braking action on the drums 2 and 7.

According to a particularly important feature of the present invention, a rocker 53, provided with two side cheek members 53^a pivoted at 54, is mounted on the shaft 9 of the motor. The angular connection between the rocker 53 and the shaft 9 is ensured by friction discs 55 which are put out of action as soon as the cheek members 53^a are moved away from each other. The rocker 53 is held in mean position, in which the gear 17^a does not mesh with the toothed wheels 18 and 19, through the medium of at least one resiliently distortable blade 57 rigid, at one of its ends at 58, with the rocker 53 and extending between two fixed abutments 59, which latter are preferably provided with rollers.

The closing of the circuit of the motor ensures the rotation, in the desired direction, of the shaft 9 of the motor 1; this shaft 9 drives, in the same direction, the rocker 53 which engages either with a wedge 61, or with a wedge 62 which is thereby inserted between the cheek members 53^a restored to closing position by springs 63. The cheek members or jaws 53^a are thus slightly moved apart so as to put out of action the friction clutch 55 and thereby release the rocker from the motor shaft 9.

The wedges 61 and 62 are so devised as to constitute contacts, in such a manner that by engagement of the rocker 53 with one of these contacts 61 or 62, the circuit of one of the electromagnets 61^a or 62^a is closed, without having to manually maintain the initial contact of the main circuit. The energized electromagnet holds the rocker 53 in position for securely holding the gear 17^a in engagement with one of the gears 18 or 19 according as the flexible surface is extended or retracted. At each end of the displacement

of the flexible surface, in one direction or the other, this flexible surface acts on switches opening the circuit of the motor and that of the locking electromagnet, so as to allow the rocker to return to its mean position under the action of its spring 57, whilst ensuring the engagement of the friction clutch 55 allowing to render the rocker 53 rigid with the motor shaft 9. The various control members have thus been restored to their initial position for allowing, in the same conditions as those previously indicated, a further displacement of the movable flexible surface.

The two cables 3, which exert a pull on the flexible surfaces and wind up on the drum 2, are guided by any suitable means, and particularly by a screw and nut device 65 for causing the cables to helically wind up on the drum.

It will be noted, according to an important feature of the present invention, the box or casing 66, constituting the end of a movable wing, is rigid and perfectly guided on the fixed portion 67 of the wing. The movable flexible wing is secured to the rigid box or casing which exerts a pull on this flexible wing during unwinding and allows this flexible surface to be extended out during flight at high speed. The movable box or casing 66 always remains on the fixed portion 67, even when the airplane is taken to pieces for shipment. In this case, the wing which is connected by false ribs to the box or casing, is disengaged from the latter by removing the screws 66^a and 66^b. In this way, the adjustment of the pulling cables is not disturbed.

For avoiding side pulls on the flexible surface when the latter is being unwound and any wedging of the movable box or casing 66 (Fig. 3) on the fixed portion 67 of the wing, the movable box or casing is provided with a carriage 68 guided on the leading edge 69 of the fixed wing. This carriage is provided with wheels 70 and 71 so as to exert, through cables 72 and 73, a pull on the ribs absorbing the oblique stresses. Such a device is more particularly illustrated in Figs. 4, 5 and 6.

Figs. 7 and 8 diagrammatically illustrate a form of construction of a device for actuating a shutter 75 pivoted at 76 on the fuselage 77 of the airplane, and which, in closed position, constitutes a portion of the covering of this fuselage. This shutter 75, illustrated in full lines in its open position, and in dot and dash lines in its closed position, controls an opening 78 through which the movable flexible surface can move, this shutter also constituting a slide or a guide incline for the displacement of this flexible surface.

The shutter 75 is provided with an arm 79 to the end of which are pivoted, through the medium of a member 80 mounted, by means of a rubber block, on a pivot pin 81 of the arm 79, on the one hand, an elastic member 81 connected to a fixed point 82 and, on the other hand, a cable 83 passing on guide pulleys 84 and 85 and terminating in an eye 86. The latter can engage either with a hook 87 rigid with the movable flexible surface and secured to the movable box or casing 66, or with a rocker 88 pivoted about a fixed point 89.

The operation of this device is as follows:

The eye 86 being initially engaged with the hook 87 rigid with the movable flexible surface, the displacement of the latter in the direction for unwinding (arrow 90) causes the actuation of the cable 83 which causes the shutter 75 to pivot in the direction of the arrow 91 for opening said 75

shutter and thereby increasing the tension of the elastic member 81, which is initially stretched to a certain degree for holding the shutter 75 in closed position.

- 5 After a slight initial unwinding movement of the movable flexible surface, the hook 87, or an abutment adjacent to the latter, acts on the arm 92 of the rocker 88 which is moved in the direction of the arrow 93, actuating the eye 86 which is released from the hook 87 and held stationary in a notch 94 of the rocker 88. The movable flexible surface continues its movement, the shutter 75 being held open and the eye 86 being held stationary by the rocker.
- 15 At the end of the retracting movement of the movable flexible surface, the hook 87, or an abutment adjacent to the latter, acts on the arm 95 of the rocker 88 for angularly moving the latter in the direction of the arrow 96. This movement releases the eye 86 which engages with the hook 87 and moves with the flexible surface in the direction of the arrow 97 for a relatively short distance of the end of the retracting movement, this allowing, under the action of the elastic member 81, to close the shutter 75.

Independently of the function previously indicated, the device illustrated in Figs. 7 and 8, fulfills another very important function when both movable flexible surfaces of one and the same wing do not reach the retracted position rigorously at the same time. The flexible wing retracted with a certain lead owing to the variations in the winding up on its corresponding drum, opens the circuit of the driving motor and the lagging flexible wing is then automatically moved to the end abutment by the corresponding elastic member. The unavoidable variations occurring in the winding up operation are thus automatically compensated. Moreover, the end box or casing 66 closes the connecting cowling between the wing and the fuselage 86a.

The diagrammatic view of Fig. 9 shows an example of an electric installation for controlling the movement of the drums on which wind the flexible surfaces and of the drums on which wind the cables, which have just been described.

In this diagrammatic view, 100 designates the armature of the motor which drives the rocker 53; 101 designates the field winding the direction of energization of which is constant, the change in the direction of rotation of the motor being obtained by reversal of the current in the armature. 102 and 103 designate movable contacts normally restored by springs to the position they occupy in the drawings and which can be respectively moved in contact with fixed keys 104 and 105 when the electromagnets 106 and 107 are energized. 108 and 109 designate electromagnets the energization of which holds the beam in position for closing contacts 110 and 111. 112 and 113 designate "extreme spreading out" switches for the flexible surfaces. They are closed when the flexible surfaces are retracted and open when they reach the end of their extension movement.

65 114 and 115 designate the "extreme retracting" switches. They are closed when the flexible surfaces are extended and are automatically opened when they reach the end of their retracting movement. 116 and 117 designate double contact switches operated by the pilot. The switch 116 is designated by the expression "spreading out" knob and the switch 117 by the expression "retracting knob". Normally, when these knobs are not acted upon, the contacts are closed at 118 and 119 and open at 120 and 121. By a single opera-

tion, by opening the contacts at 118 or 119, the contacts are closed at 120 or 121. 122 designates a master switch; the installation can operate only if this switch is closed.

The source of current supply feeding the installation is shown as being constituted by a battery 123.

The operation of the installation is as follows:

The switch 122 being closed and all the contacts being in the position shown in the diagram, the flexible surfaces are retracted and wound on their drums.

For spreading them out, the pilot presses upon the spreading out knob 116. The contact 118 is opened and the contact 120 is closed. A circuit 15 is closed from positive pole of the battery 123, through switch 122, contact 119, wire 124, contact 120, wire 125, wire 126, switch 112, wire 127, switch 113, wire 128, electromagnet 107 to negative pole of the battery. 20

The electromagnet 107 being energized, it closes the contacts at 103—105. A second circuit is closed from positive pole of the battery, through field winding 101, right-hand contact 103—105, wire 129, armature 100 of the motor, wire 130, left-hand contacts 103—105, to negative pole of the battery. The motor starts in the direction of the arrow 131, actuating, as explained above, the beam 53 which closes the contact 110, the latter short-circuiting the contact at 120. The pilot can 30 therefore release the knob 116 which closes the contact at 118 and opens it at 120, the motor continues to rotate and the flexible surfaces spread out along their fixed planes. On the other hand, the positive pole of the battery being connected to 35 the wire 128 as just stated, the electromagnet 108 is energized through the wire 132, the latter being constantly connected to the negative pole of the battery. The energization of the electromagnet 108 holds the beam in position for closing the contact 110, notwithstanding the action of the resilient means tending to restore it to the mean position it occupies in the diagram. 40

If it is assumed that the pilot, for any reason whatever, desires to stop and wind up again the flexible surfaces in course of extension, he presses upon the retracting knob 117 for opening the contact at 119 and closing it at 121. The opening of the contact 119 opens the circuit previously closed through the switch 122, wire 124, contact 110, etc. The electromagnet 107 is no longer energized; the contacts are opened at 103—105 and the motor is stopped. On the other hand, owing to the fact that the contact is opened at 119, the wire 128 is no longer connected to the positive pole of the battery and the electromagnet 108 is no longer energized; the beam 53 is restored to the mean position it occupies in the diagram. 55

The same effects would be produced if the flexible surfaces were spread out to the maximum extent as, at the end of their movement, they act on the contacts 112 and 113 for opening them.

But, whether the knob 117 is acted upon when the flexible surfaces are in course of extension or when they are completely spread out, the following effects occur:

The contact being closed at 121 and opened at 119, a circuit is closed through: positive pole of the battery 123, switch 122, contact 118, wire 133, 70 contact 121, wire 134, contacts 115 and 114, wire 135, electromagnet 106, and negative pole of the battery 123.

The electromagnet 106 being energized, it closes the contacts at 102—104. The motor starts 75

in the direction of the arrow 136 and the beam 53 closes the contact 111, the latter short-circuiting the contact 121 the opening of which, when the knob 117 is released, no longer intervenes in 5 the operation in progress. The electromagnet 109 is energized and holds the beam 53 in position for closing the contact 111.

It will be seen that the flexible surfaces "move in" until the spreading out knob 116 is pressed 10 upon, or, when they reach the end of their movement, they act on the switches 114 and 115 for opening them.

For facilitating the operations, a board is arranged in the pilot's cockpit, within reach of 15 the pilot. The board shown in Fig. 10 corresponds to a biplane provided with two distinct motors for independent control of the flexible surfaces of the upper planes and of the flexible surfaces of the lower planes.

20 On this board, 116 and 117 respectively designate the retracting and spreading out knobs shown in the diagram of Fig. 9, for the upper planes. 116a and 117a designate the corresponding knobs for the lower planes. 137 and 25 138 designate ammeters. At 139 is provided an indicator showing the charge of the batteries. At 140 and 140a are arranged the knobs of the master switches for the upper and lower planes. Supervision means are moreover provided and 30 are constituted by lamps of different colours.

What I claim as my invention and desire to secure by Letters Patent is:

1. In an airplane, fixed planes, winding drums, 35 flexible planes wound on said winding drums, a reversible motor, a cable connected with the free and of each flexible plane, a winding drum for said cables, means connecting the drums of the flexible planes, gearings connecting said motor with the first and second mentioned drums for 40 actuating said drums and extending and retracting the flexible planes, said gearings including free running elements, said motor being adapted, during operation, to selectively actuate said drums and extend or retract said flexible planes in dependence on the direction of movement of said motor, and means for interrupting operation of 45 said motor when said flexible planes reach the end of their extension and retraction movements.

2. In an airplane, fixed planes, winding drums, 50 flexible planes wound on said winding drums, a reversible motor, a cable connected with the free end of each flexible plane, a winding drum for said cables, means connecting the drums of the flexible planes, a gearing connecting the motor 55 with the drum for the cable, said motor including a motor shaft, a rocker mounted coaxially with the motor shaft, a pinion on the motor shaft, and a second pinion journaled on the rocker and permanently meshing with the first mentioned 60 pinion, separate gear trains both operatively connected with the drums of the flexible planes, the second mentioned pinion being adapted to be brought into operative relation with one or the other of said gear trains during rocking movement of the rocker, a circuit including said motor, means actuated by said rocker to close said circuit, and means independent of the first mentioned circuit, closing means for interrupting 65 operation of said motor when said flexible planes

reach the end of their extension and retraction movements.

3. In an airplane, fixed planes, winding drums, flexible planes wound on said winding drums, a reversible motor, a cable connected with the free end of each flexible plane, a winding drum for said cables, means connecting the drums of the flexible planes, a gear train connecting the motor with the drum for the cable, said motor including a motor shaft, a rocker mounted coaxially of said shaft, separate gear trains both connected with the cable of the flexible planes, permanently meshing pinions mounted on the motor shaft and rocker, the rocker carried pinion being alternately engageable with the respective 15 last mentioned gear trains, means normally tending to move the rocker to an intermediate position, clutch elements normally establishing a driving connection between the motor shaft and said rocker whereby the latter is coupled with 20 and oscillated by said motor shaft, means engageable by the rocker to release said clutch elements and permit the motor shaft to revolve independently of the rocker, an electric circuit including said motor, means controlled by said 25 rocker for closing said circuit and maintaining the latter closed during the extension and retraction movements of the flexible planes, and means for interrupting operation of said motor when said flexible planes reach the end of their 30 extension or retraction movements.

4. An arrangement as claimed in claim 3 characterized by the provision of electro-magnetic means interposed in said circuit and arranged at opposite sides of said rocker and coact- 35 ing therewith to retain said rocker in adjusted position during the extension and retraction movement of the flexible planes.

5. An arrangement as claimed in claim 1 characterized in that said flexible planes include 40 ribs and a rigid casing at the end of each flexible plane, guide pulleys arranged in each casing and movable along the leading edge of the fixed planes, a movable bearing for at least one of said 45 guide pulleys, and a tension cable for connecting the movable bearing to the ribs of each flexible plane.

6. An arrangement as claimed in claim 1, characterized in that said flexible planes include 50 ribs and a rigid casing at the end of each flexible plane, guide pulleys arranged in each casing and movable along the leading edge of the fixed planes, a movable bearing for at least one of said 55 guide pulleys, and a tension cable for connecting the movable bearing to the ribs of each flexible plane, said drums being mounted on the fuselage of the airplane and the latter being provided with openings for the passage of said casings and flexible planes, a shutter normally closing each opening, and a tension cable nor- 60 mally tending to close each shutter, a second cable connected with each shutter for moving the latter to open position, an eye at the end of the second cable, a hook pivoted to each fixed plane and engageable by said eye for retaining the 65 shutter in open position, and a hook carried by each rigid casing adapted to disengage said eye from said pivoted hook when the flexible plane is retracted.
